UNITED STATES PATENT OFFICE.

JOSEPH A. GAGNON, OF SOUTH FITCHBURG, MASSACHUSETTS, ASSIGNOR TO CROMPTON & KNOWLES LOOM WORKS, A CORPORATION OF MASSACHUSETTS.

STOP-MOTION FOR LOOMS.

1,369,417.

Specification of Letters Patent. Patented Feb. 22, 1921.

Application filed May 2, 1917. Serial No. 166,034.

To all whom it may concern:

Be it known that I, JOSEPH A. GAGNON, citizen of the United States, residing at South Fitchburg, in the county of Worcester 5 and State of Massachusetts, have invented new and useful Improvements in Stop-Motions for Looms, of which the following is a specification.

This invention relates to improvements in 10 automatic stop motions for looms. More particularly it is the object of the invention to improve upon the type of stop motion in which the lathe of a loom automatically turns off the power and stops the loom on its 15 forward swing whenever the shuttle has failed to lay a thread of weft or filling. It is here illustrated as it may be applied to that particular type of stop motion mechanism in which a dagger operating on the 20 hit or miss principle is thrown forward by the lathe, so as to "hit" a tumbler and thus to throw the shipper rod if the weft thread has not been laid, or is broken, but "to miss" the tumbler if the thread has been laid, as in 25 normal running.

The object of the invention is to increase the sensitiveness; to simplify the construction; to eliminate sundry mechanical elements and combinations of mechanism which 30 have heretofore been thought necessary in such apparatus and to substitute improved devices; to reduce the cost of the mechanism; also to provide for applying the brake to a loom more quickly; using a milder spring on 35 the brake and thus adding to the life of gears, brake lining and incidental parts; and to insure certainty of action of the stop motion, with the result that the loom makes fewer mispicks and better cloth than without the invention, and that the weaver does 40 not have to waste so much time in correcting mispicks. It is also the object of the invention to provide mechanism having the other advantages that are incidental to the 45 construction herein disclosed. The invention provides a cam for releasing the usual brake rod from the latch that holds it. Such release turns off the power and applies the brake in the usual or in any suitable way. 50 The cam is a light, sliding block actuated by very light mechanism, such as a cord or wire which need be only strong enough to transmit a gentle pull. The cam and its cord are normally held by a light spring in 55 a position corresponding to the inactive po-

sition of the brake rod. In order to apply the brake it is only necessary to overcome this light spring, and the spring that holds the brake rod latched. After such release the parts are instantly drawn back, and the 60 tumbler reset, by the said light spring, acting through the cord in reverse direction. The action of the improved apparatus is so rapid that propulsion of the tumbler by the dagger for a shorter distance than heretofore suffices. The cam block travels transversely of the brake rod, and so can have as long a travel as is desired, but as a short travel and complete execution of its duty in the earliest part of the tumbler's motion is 65 preferable, means is therefore provided for disconnecting the dagger from the tumbler promptly after the tumbler actuation begins, thus further reducing the stress and wear of parts. The invention may be embodied in 70 various arrangements of mechanism. It is intended that the patent shall cover by suitable expression in the appended claims whatever features of patentable novelty exists in the invention disclosed. One arrangement 75 of mechanism and certain modifications thereof are illustrated in the accompanying drawings, in which;

Figure 1 is a perspective, and to some extent a diagrammatical, representation of an 85 embodiment of the invention, showing its installation on a loom, the view being taken from the right hand end;

Fig. 2 is an elevation, viewed from the 90 left hand end, of certain details of the parts shown in Fig. 1, on a larger scale;

Fig. 3 is an elevation, viewed from the 95 right hand end, of other details which are partly seen in Fig. 1, in different relative positions, on a scale more nearly approaching that of Fig. 1;

Fig. 4 is a plan of a detail, on a large scale; and

Fig. 5 is a modified arrangement, corresponding to part of Fig. 1; 100

Fig. 6 represents a modified form of a detail; and

Fig. 7 is a perspective view similar to Fig. 1 but showing another slight modification. 105

Referring to the drawings, 10 indicates the lathe of a loom, 11 the front stationary beam of the frame, 12 a casting or fixture thereon for supporting part of the stop motion which is about to be described, and 13 a 110

tumbler supported by and pivoted on said fixture at 14. The brake rod 15 is connected by suitable means, not shown, to suitable mechanism for cutting off the power by which the loom is driven, and is also connected with a lever 16 for applying a brake 17. On this brake rod is a spring 18 which tends to push it upward, acting between two collars, one of which 19, is rigidly supported from the frame of the machine and is loosely penetrated by the brake rod 15, and a collar 20 fast on the brake rod. A pedal 21 provided on this rod, permits the operator to depress it. The brake rod has a latch consisting of a notch and abutment 22 on its upper part, and the frame of the loom carries a casting having a keeper 23 adapted to engage against this abutment 22. These two, with a spring 24 which tends to force them together, constitute a latch so that they engage whenever they are opposite each other. By depression of the pedal 21, the brake rod 15 is depressed with the result that the brake 17 is released and, after the depression has been carried to the normal extent, the two latch members 22, 23 become engaged, and so hold the brake rod down with the brake released. The power is controlled by a separate lever 25 having a handle 26 conveniently located at the end of the loom. This is seen in Fig. 3 but is omitted in Fig. 1 for the sake of more clearly showing parts behind it. A link 27 and a connecting rod 28 lead to the power control. The operator's handle 26 is on the upper end of lever 25. On its lower end is a boss 29 adapted to be engaged by a cam surface 30 on the vertically moving brake rod. When the loom is running under power these parts are in engagement or ready for engagement as illustrated in Fig. 1; but when the brake rod is released and flies up, the cam 30 throws the boss 29 and with it the lever 25 so that the lever 25 assumes the position illustrated in Fig. 3, thereby swinging link 27 and turning off the power. The brake rod meanwhile rises to the position illustrated in Fig. 3. Depression of the brake rod by the pedal permits the operator to work the loom by hand, but the lever 25 stands unmoved, nevertheless, until the operator by pulling the handle 26 throws the boss 29 into contact position, to be again engaged by the cam 30; and at the same time throws power control link 27 and its connecting rod 28 into the running position.

The invention is concerned with the means for automatically releasing the latch 22, 23 of the brake rod 15. This effect is produced by a cam surface 31 on a sliding block 32, which is suitably mounted in a casting 33 supported by the frame 11. The said casting is penetrated vertically by an oblong hole 34, through which the brake rod 15 travels up and down, with its spring 24 and

latch 22, the inside of this hole having the keeper 23. It is penetrated horizontally, across the lower entrance of the vertical hole, by another hole in which the cam block 32 is guided. The cam block itself, fitting loosely therein, projects horizontally across the end of the vertical hole 34 in which the brake rod stands in such a manner that the depressed surface 35 of the cam is approximately flush with the edge of the vertical hole 34, under the keeper 23, and so does not interfere with the complete latching of the brake rod. The cam rise 31 normally is beyond, toward the end of the loom, to the right hand in Figs. 1 and 4 and projects horizontally so that, when the cam block 32 is pulled to the left its rise 31 gradually pushes the brake rod 15 away from the keeper 23 until it is unlatched and flies upward. This applies the brake and turns off the power as above explained, and so stops the loom.

The total travel of the cam block requisite to effect this easily may be only about three eighths of an inch in an ordinary installation. The invention provides means to accomplish it by very light mechanism which transmits a simple pull. To this end the cam block 32 is attached to a lever 36, which is fulcrumed at 37 on the casting 33 and is adapted to be pulled to the left (in Fig. 1), by a suitable tie 40, there represented as a wire. The points of attachment of the tie 40 and cam block 32 fall on the same side of the fulcrum 37, with the leverage in favor of the cam block. The tie 40 reaches to the middle of the front of the loom, where, under the beam 11, it is attached to a bell crank 41 from which another tie 42 extends to an arm depending from the tumbler 13. This tumbler is in the shape of a bell crank, of which one arm is attached to the tie and the other arm is in position to be engaged by the dagger 44 on any forward swing of the lathe in a manner already well known.

An alternative arrangement is illustrated in Fig. 5 where the differences in construction are apparent upon comparison with the closely adjacent part of Fig. 1. In Fig. 5 a flexible tie 40' is represented, which may be piano wire, or even a simple cord, passing around a guide or pulley 41' directly to a tumbler 13' which, like the tumbler 13 of Fig. 1, is a bell crank with one arm positioned to receive the thrust of the dagger, but has its other arm connected to the lever 36 with no intermediary except this single flexible tie. In Fig. 5 the transmitting arm extends horizontally from the pivot 14 of the tumbler to a position under the sheave 41', and thus takes the place of both the tie 42 and the lower arm of tumbler 13 of Fig. 1. A style of tumbler 13'' like that shown in Fig. 6 may be substituted for the shape 13' shown in Fig. 5.

The operation of the dagger 44 may be controlled in any ordinary or suitable way. The drawing illustrates a thread detector, comprising feeler wires 45, whose descent is 5 normally arrested by the weft thread thus preventing descent of the dagger 44 to the level of the tumbler. When the feeler wires 45 are not thus arrested, as when a weft thread breaks or is not laid, the dagger 44 10 is not arrested; and upon its further descent it continues along on its guiding cam 46, and engages and drives ahead of it the upward projecting end of the tumbler. This, connected through its bell crank's lower 15 arm, imparts a pull to the tie 42, which is transmitted by bell crank 41 to tie 40 and by that to lever 36 and so to the cam block 32. The movement of the tumbler necessary for pulling the cam block its short requisite 20 distance is small; but this may be regulated according to the will of the designer by taking advantage of the numerous opportunities for change of leverage, involved in the two bell cranks and the lever 36. Preferably the fixture 12 which supports the bell 25 crank 13 has a hump 47 beside the part of the tumbler which is engaged by the dagger, such that as the dagger travels along while engaging the end of the tumbler it rises on 30 this hump and quickly gets high enough to clear the tumbler so that the remainder of its travel is idle. The lever 36 has a spring 48 tending to draw it and the whole system of parts into the normal position of rest, 35 which is to the right on Fig. 1. This spring, which may be light because the parts are all so light throws cam block, ties and tumbler immediately back into their normal positions as soon as the dagger has cleared the 40 tumbler. The single pull of the cam block during the brief engagement of dagger and tumbler is effective to release the brake lever 15 and incidentally to turn the rod 49 as the power lever 25 is thrown, these two being 45 fast together. And the rod 49 has a spring 50 which is thus thrown downward and so presses on a bell crank 51 that sets up a shield 52 which, when up, prevents the dagger 44 from descending low enough to engage the tumbler 13. This shield position, 50 illustrated in Fig. 2, is useful when the loom is being operated by hand. Each time that the dagger then reaches the abutment 53 on the forward end of this shield, the spring 55 50 and bell crank 51 yield, and then they push the shield back again when the dagger retreats. This happens as long as the power lever 25 occupies the position of Fig. 3; but it ceases when the operator moves the handle 60 26 so as to turn the boss 29 back to its position illustrated in Fig. 1, which action throws link 27 and the power connection 28 so that the loom is operated by power. In doing so it turns the rod 49 and thus lifts 65 spring 50.

The apparatus thus described for connecting the tumbler 13 so as to release the brake rod and for automatically returning the tumbler and the brake releasing means to position for a repetition of the operation is 70 simple and light and has the advantage that it supplants parts on looms as at present built that are more complicated and have considerably more inertia. The parts thus supplanted have such inertia and such friction in operation, and work so slowly, that a powerful spring on the brake is required, in order to expedite the stopping, and this results in rapid wear and occasional breakage 75 of the gearing which connects it. Owing to 80 the inertia of the brake releasing mechanism a powerful impulse has to be delivered by the dagger upon the tumbler; and in practice this has been worked out by distributing the 85 stroke over a considerable distance through which the dagger pushes the tumbler before the release is accomplished.

The stroke of the dagger which releases the brake must be completed and the frictional drag of the brake which stops the 90 loom must begin during the forward swing of the lathe, the one being completed before the other begins; and it is an aim or ideal of the device as a whole to bring the loom to rest during the very swing of the lathe 95 in which the mispick has occurred, and in which the dagger stroke is made. Hence the invention by requiring only a very short part of the swing of the lathe for releasing the brake, renders available the time which 100 corresponds to a very much larger part of its swing for bringing the loom to rest during that swing. From this follows an elimination of the at present customary rapid wear and consequent necessary replacement 105 of parts associated with the brake mechanism. The gentler application of the brake now possible relieves the gearing from wear and from occasional snapping of teeth and from getting loose. Also the certainty 110 and promptness of the stoppage reduces the number of mispicks which occur in the cloth, with resulting better cloth, and with less waste time of the wearer in correcting mispicks, with less waste material that has 115 to be pulled out in correcting the mispick, and with increase of the time in which the machine is productively employed. As the impulse required to release the brake is so little, as compared with prior construction, 120 the dagger and the tumbler and their related parts are subject to much less shock of contact. This effects a material saving in breakage and damage to these parts. Consequently the maintenance cost of the 125 loom is materially lower. The described stop motion is easy to apply to a loom and is relatively inexpensive to make and install; and, as the duty of the parts is so light, there is little or nothing to interfere 130

with their continued perfect action in the manner intended without getting out of order. Moreover the increased sensitiveness which the invention attains makes less tendency for the dagger to fail to knock off the brake when the loom is being run at high speed, and also time is saved which hitherto has been requisite for adjusting the various parts of the stop motion, so that 10 they will work to the best advantage after a change in speed of weaving.

In considering variations of the particular device that is illustrated, it will be observed that as the force applied to the end 15 of the lever 36 acts in the same direction as the force which is applied to the cam 32, the tie 40 might be attached directly thereto. A convenient arrangement is shown in Fig. 7, in which the tie 40 connects the bell crank 20 41 directly to the cam block 32, omitting the lever 36 shown in Fig. 1. The rod 15 plays between this cam and the spring 24, both of which are engaged by the opposite sides of the same block or casting 33. Hence the 25 disengagement of the rod 15 from its latch is effected without any outside base for the action being requisite, by a mere wedging effect as the cam surface 31 of the block 32 is drawn through the hole provided in block 33. Being a simple, spreading action, not 30 dependent upon momentum but rather on the precision with which the cam block is guided, this can be effected by a simple pull; and the pull is not necessarily applied precisely in the direction of the cam block's motion. This affords considerable latitude 35 to the convenience of the designer in planning the connection from the thread detecting device, wherever it be in the middle portion of the loom, to the brake releasing device, in whatever part of the loom that is situated. The spring 48 which is attached 40 to the lever 36 may be equally said to be attached to the cam block 32, and by its connection through the tie 40 constitutes automatic means for returning both the cam and 45 the tumbler to a zero position which is precisely determinable by the location of the stop pin 54.

50 I claim as my invention:—

1. In a loom having a shipper, a filling stop motion, with a dagger mounted on the lay, and a member mounted on a fixed pivot and positioned for engagement by said dagger on filling failure, in combination, a brake rod movable to inoperative position independently of the shipper, means to hold said brake rod in inoperative position, a cam adjacent said holding means effective to release said brake rod, and operative connections 55 between said member and said cam movable longitudinally to release said brake rod, said shipper being moved by said released brake rod to throw off the power.
- 60 2. In a loom having a filling stop motion,

with a dagger mounted on the lay, and a member mounted on a fixed pivot and positioned for engagement by said dagger on filling failure, in combination, a brake rod movable to inoperative position independently of the shipper, means to hold said brake rod in inoperative position, a cam adjacent said holding means effective to release said brake rod, operative connections 70 between said member and said cam movable longitudinally to release said brake rod, and means to return said cam and member to normal position independently of the position of said brake rod.

3. In a loom having a shipper, a filling 80 stop motion, with a dagger mounted on the lay, and a member mounted on a fixed pivot and positioned for engagement by said dagger on filling failure, in combination, a brake rod movable to inoperative position independently of the shipper, means to hold said brake rod in inoperative position, a cam block adjacent said holding means effective to release said brake rod, and operative connections 85 between said member and said cam block, said connections including a transmitting element directly connected to said cam block and movable longitudinally to position said cam block by a direct pull which moves said cam block bodily with a 90 straight line movement to release the brake rod.

4. A stop motion for looms including in combination a weft thread detecting device; a movable element controlled thereby; a 100 tumbler adapted to be engaged by said element when engagement is not prevented by said thread detecting device; mechanism to stop the loom and means to hold and to release said mechanism, comprising a rod of 105 said mechanism, a block through which it passes, and a latch, a spring, and a cam connected with said tumbler; the cam and spring working oppositely in the block with respect to the latch.

5. A stop motion for looms including in combination a weft thread detecting device; a movable element controlled thereby; a tumbler adapted to be engaged by said element when engagement is not prevented by 110 said thread detecting device; mechanism to stop the loom; and means to hold and to release said mechanism comprising a rod of said mechanism, a block, a latch, a spring, and a cam connected with said tumbler; the 120 spring tending to cause engagement of the latch; and the block having a vertical opening wherein the rod is guided, and an adjacent horizontal opening wherein the cam is guided, thereby opposing the spring.

6. A stop motion for looms including in combination a weft thread detecting device; a movable element controlled thereby; a tumbler adapted to be engaged and driven by said element when such engagement is 125 130

not prevented by said thread detecting device; a stationary cam adapted to be likewise engaged by said element and to deflect said element gradually from the path of the 5 tumbler and so to disengage it therefrom; mechanism to stop the loom; a latch for holding said mechanism out of action and releasing means therefor; and means where-

by the driving of the tumbler actuates the releasing means. 10
